UNITED STATES PATENT OFFICE.

LEVIN H. CLOGG, OF NEW YORK, N. Y.

DESIGN FOR A PENDANT FOR UMBRELLA-HANDLES.

SPECIFICATION forming part of Design No. 28,222, dated February 1, 1898.

Application filed September 18, 1897. Serial No. 652,194. Term of patent 3½ years.

To all whom it may concern:

Be it known that I, LEVIN H. CLOGG, a citizen of the United States, residing in the city, county, and State of New York, have invented and produced a new and original Design for Pendants for Umbrellas, of which the following is a clear and sufficient specification.

My design consists of a band, at one side of which is a central knot A. To one side of this knot arises a loop-shaped portion C and from the other side depends a tasseled por-

tion b, the three features of the design being unitary.

What I claim is—

The design for a pendant for umbrella-handles substantially as described.

In witness whereof I have hereunto set my hand this 2d day of September, 1897.

LEVIN H. CLOGG.
